SHOCK-ABSORBING AND MOTION-IMPEL-LING MEANS FOR CINEMATOGRAPHS

Irving Cisski, Schiller Park, Ill., assignor to
Ampro Corporation, Chicago, Ill., a corpora-
tion of Illinois

Application January 12, 1946, Serial No. 640,955

4 Claims. (Cl. 185—37)

1

This invention relates to shock-absorbing and motion-impelling means for the operating mechanism for cinematographs.

In the operation of cinematographs, two operational problems are encountered. The first has to do with the need for dissipating the kinetic energy of the rapidly moving parts intermediate the motor and the film-shutter and -transport mechanism when the action of the latter is suddenly checked. The second has to do with instantly impelling movement in the film-shutter and -transport mechanism when it is subsequently released and thereby overcoming the lag that occurs in the transmission of motion from the motor to said mechanism.

Obviously, the securing of the best results requires that the film-shutter and -transport mechanism should be stopped and started in the briefest possible fraction of a second. That necessitates placing the means which controls the arrest and the release of the film-shutter and -transport mechanism at the nearest possible point to that mechanism. The nearest point at which that can be effected is the means which most directly causes the movement of the film-shutter and -transport mechanism, namely, the drive shaft for that mechanism.

Between the aforesaid shaft and the motor is a train of gears which, when in motion, creates a considerable amount of kinetic energy. Thus, when instantly checking the shaft which most directly causes the operation of the film-shutter and -transport mechanism, it is advantageous to provide means for absorbing the kinetic energy created by this train of gears.

However, the efficiency of a cinematograph, and the personal satisfaction which the operator thereof derives from its use, is dependent upon how quickly the movement of the film-shutter and -transport mechanism can be effected following the operator's release of power from the motor. Obviously, it takes a measure of time for the motor to communicate the torque thereof to the driving shaft for the film-shutter and -transport mechanism, after the stopping means for such mechanism has been released. It is, therefore, also advantageous to provide means for impelling the initial movement of the drive shaft for the film-shutter and -transport mechanism, the instant that mechanism has been released, thereby overcoming the lag in the transmission of the force of the starting torque of the motor to the film-shutter and -transport mechanism.

The main objects of this invention, therefore, are to provide an improved driving means for the

2

film-shutter and -transport mechanism of a cinematograph which acts to store up the kinetic energy existent in the motor and the means connecting it with the film-shutter and -transport mechanism, when the latter is brought to a sudden stop, and subsequently to use that stored-up energy to overcome the static inertia of the film-shutter and -transport mechanism when it is subsequently released for operation; and to provide a driving mechanism of this kind including a yielding element therein which will permit one part thereof to slightly overrun another part when the rotation of the latter is suddenly checked, thereby storing up in said yielding-means, for subsequent release to initiate the movement of the film-shutter and -transport mechanism, the kinetic energy existent in the driving mechanism when the film-shutter and -transport mechanism is suddenly checked.

20 The preferred embodiment of this invention is shown in the accompanying drawings on a scale considerably larger than actual size, in which,

Fig. 1 is a transverse sectional view of a motion picture camera wherein has been incorporated the improved means for storing up the kinetic energy of the operating parts and subsequently releasing it to overcome the inertia of the film-shutter and -transport mechanism;

Fig. 2 is a detail view, taken on the line 2—2 of Fig. 1, showing the trigger mechanism by which the movement of the film-shutter and -transport mechanism is checked and released; and

Fig. 3 is a longitudinal sectional view taken on the line 3—3 of Fig. 1.

35 A motion picture camera embodying this improved means, for storing up and subsequently releasing the kinetic energy of the motor-driven means, comprises, a housing 10 divided by a vertical partition 11 to form a magazine compartment 12 and an operating-mechanism compartment 13, in the latter of which is mounted a motor-driven gear train 14 connected to operate a film-shutter and -transport mechanism, as permitted by the control means 15, if said control means is not rendered inoperative by the motor-torque control means 16 or the motor-control-readying-mechanism cam 17. The gear train 14 incorporates therein a preferred form of the improved shock-absorbing and motion-impelling means 18 constructed in accordance with this invention.

The gear train 14, as shown in Fig. 3, is journaled on the housing 10 and partition 11, within the operating-mechanism compartment 13. Through the medium of the shock-absorbing

and motion-impelling means 18, to be more fully hereinafter described, the gear train 14 drives the spiral gears 19 and 20 which are respectively connected to operate a film-shutter and transport mechanism and a governor-control mechanism. These latter mechanisms are not shown herein since they are not directly related to the disclosure. However, they are fully shown and described in co-pending applications Serial No. 640,952, filed January 12, 1946, and Serial No. 640,950, filed January 12, 1946.

The gear 19 is connected by a spiral gear 21 to operate the drive shaft 22, for the aforementioned film-shutter and -transport mechanism, as permitted by the operative readiness of the motor-control means 15.

The motor-control means 15 is fully shown and described in co-pending application Serial No. 640,949, filed January 12, 1946, now Patent No. 2,442,756. Only such part of that means is illustrated in these views as is necessary to understand the construction and operation of this invention. Such a motor-control means includes a trigger bar 23 which is adapted to be actuated by a suitable starting dial (not shown) for the purpose of moving the stops 24 and 25 into and out of the path of a shoulder 26 on a trigger cam 27 mounted on the film-shutter and -transport mechanism drive shaft 22. The connection of the starting dial with the trigger bar 23 is through the medium of a pin-retracting lever 28 rockingly mounted on a slidable pivot (not shown herein) on said trigger bar 23. A pin 29, carried by said pin-retracting lever 28, is normally held in the bottom of the transverse part of the T-shaped slot 30, formed in said trigger bar 23. Therefore, when the lever 28 is shifted either to the right or left of Fig. 1 it serves to shift the trigger bar 23 to move one or the other of the stops 24 or 25 into or out of the path of the shoulder 26 on the trigger cam 27, as will more fully appear in the aforesaid Patent 2,442,756.

Associated with the trigger bar 23 is a cam rocker arm 31 and a cam lever 32. The respective shifting of these parts, by the motor-torque control means 16 or the cam 17, will effect a shifting of the pin-retracting lever 28 so as to move the pin 29 into the transverse part of the T-shaped slot 30. This will permit a shifting of the trigger bar 23 independently of the lever 28, under the influence of a spring (not shown), to its neutral position with the stop 24 in position to engage the shoulder 26 on the trigger cam 27, thereby arresting any further movement of a film-shutter and -transport mechanism.

As will be noted from Fig. 1, the cam-rocker arm 31 is pivoted at 33 adjacent to the rear portion of the trigger bar 23. The inner end of this cam-rocker arm 31 has a transversely-extending flange 34 which is adapted to engage the lower edge of the pin-retracting lever 28, when the inner end of said cam-rocker arm 31 is swung on the pivot 33. Such a swinging of the rocker arm 31 shifts the pin 29 out of the bottom of the stem part of the T-shaped slot 30 into the transverse part, to permit the release of the trigger bar 23 from the pin-retracting lever 28 as noted above, and as fully explained in the aforesaid Patent No. 2,442,756. The upper end of the member 31 is formed with a hook 35 which is engaged by a shoulder 36 on the cam lever 32. The cam lever 32 is pivoted at 37 and counterbalanced so that the end 38 thereof normally holds the shoulder 36 in contact with the hook 35 on the cam-rocker arm 31. This positions the inclined cam surface

39 in the path of the horizontally-movable cam member 17, which is actuatable to render the motor-control means 15 ineffective in the same manner as may be accomplished by the torque-control mechanism 16.

The torque-control mechanism 16, which is fully shown and described in co-pending application Serial No. 640,957, filed January 12, 1946, involves a rocker arm 40 which, so long as the torque of the motor exceeds a certain minimum, occupies the position shown in Fig. 1. As explained in the aforesaid application, Serial No. 640,957, when the torque drops below a certain predetermined minimum, the arm 40 is shifted in the direction of the arrow 41. This causes the cam end 42 of the arm 40 to contact the opposed cam surface 43 on the cam-rocker arm 31 and swing said rocker arm to press the transverse flange 34 against the pin-retracting lever 28 and lift the pin 29 into the transverse part of the T-shaped slot 30 in the trigger bar 23.

The arrangement and operation of the motor-control-readying-mechanism cam 17 is fully shown and described in co-pending application Serial No. 640,951, now Patent No. 2,443,601. The movement of this cam to the right or left of Fig. 1, to engage or disengage the cam surface 39 on the cam lever 32, is determined by the operation of mechanism associated with a film magazine adapted to be inserted in the magazine compartment 12, as will appear from the aforesaid Patent No. 2,443,601. The movement of the cam 17 to the right of Fig. 1 causes it to depress the lever 32 which elevates the forward end of the rocker arm 31 and causes the transverse flange 34 to elevate the pin-retracting lever 28 and move the pin 29 thereon into the transverse part of the T-shaped slot 30 in the trigger bar 23, for the purpose of releasing said trigger bar from the action of the starting dial.

The improved shock-absorbing and motion-impelling means 18, embodying this invention, comprises a pair of rotatable parts 44 and 45 which are rotatably connected together by means of a coiled spring 46. The parts 44 and 45 are mounted on a shaft 47, journaled in bearings 48 and 49 on opposite sides of the housing 10. The member 44 (which, for all practical purposes includes the part 44a) has fixed thereon the spiral gears 19 and 20. The former of these is connected to the spiral 21 which operates the shaft 22 whereon is mounted the trigger pawl 21.

The member 45 mounts a gear 50, to rotate therewith, which meshes with a gear 51 of the train of gears 14.

The spring 46 has the ends thereof slipped over the opposing ends of the members 44 and 45. The several convolutions at each end of the spring 46 frictionally engage the cylindrical surfaces of the members 44 and 45. So long as power is applied to the member 45 in the direction of the arrow 52 the grip of that end of the spring 46 on the member 45 is increased. The consequent revolving of the spring 46 with the member 45 tends to tighten the grip of the other end convolutions of the spring 46 on the member 44 and thereby cause it to rotate in unison with the member 45.

A spring-actuated eccentric cam 53 prevents the recoil of the spring 46 to reverse the rotation of the member 45. This eccentric 53 is mounted on a pin 54 which supports the trigger bar 23. A spring 55, embracing a bushing on the pin 54 has one end 56 bearing on the bottom of the housing 10 and the other end 57 hooked under the edge

of the eccentric 53, so as to urge the face 58 of the eccentric to engage the periphery of the spring 46 and bind against it when the spring 46 tends to recoil, following the arresting of the drive of the cinematograph motor.

This spring connection of the members 44 and 45 accomplishes two very beneficial results: first, it absorbs the shock caused by suddenly stopping the film-shutter and -transport mechanism; and secondly, it stores up the kinetic energy of the moving parts, to subsequently give an initial impulse to said film-shutter and -transport mechanism when it is again released.

When the rotation of the shaft 22 is suddenly arrested, through a shifting of the stops 24 and 25 into the path of the shoulder 26 on the cam trigger 27, the rotation of the member 44 is also instantly checked by reason of its connection through the spiral gear 19 with the gear 21. However, the shock of suddenly arresting the movement of the several parts of the gear train 14 is absorbed into the spring 46 by reason of the fact that the spring 46 will exercise a gradually increasing restraint upon the continued rotation of the part 45. Thus, the force of the kinetic energy in this rotating mass is absorbed into the spring rather than converted into vibrations dissipated through the camera mechanism.

This stored-up energy in the spring 46 is subsequently available as a booster force for impelling rotative motion in the member 44 at the instant that one of the stops 24 or 25, on the trigger bar 23, is retracted from the path of the shoulder 26 on the trigger pawl 27. Thus the film-shutter and -transport mechanism, connected with the member 44 through the medium of the spiral gears 19 and 21, has its static inertia overcome by the stored-up kinetic energy in the spring 46 and is in motion when the released torque of the motor is available for fully operating the film-shutter and -transport mechanism.

Variations and modifications in the details of structure and arrangement of the parts may be resorted to within the spirit and coverage of the appended claims.

I claim:

1. The combination of a rotating member, means movable into and out of position to check the rotation of said member, mechanism connecting said rotating member to a motor, said mechanism comprising a pair of parts operatively connected together by a resilient element adapted to stop the motor when rotation of said member is checked, to permit one of said parts to overrun the other said part when said rotation is checked and to maintain said parts at equal speeds during periods of rotation of said member, other means adapted to hold said one part in its overrun position thereby storing up the kinetic energy in said mechanism for subsequent application in overcoming the static inertia of said other part when said rotating member is released by said rotation checking means.

2. The combination of a rotating member, means movable into and out of position to check the rotation of said member, mechanism connecting said rotating member to a motor, said

mechanism comprising a pair of cylindrical parts, a coiled spring having the ends thereof frictionally embracing the respective cylindrical parts for driving one from the other, said spring having characteristics of resilience adapting it to stop the motor when rotation of said member is checked, to permit one of said parts to overrun the other said part when rotation of said member is checked, and to maintain said parts at equal speeds during periods of rotation of said member, other means adapted to hold said one part in its overrun position thereby storing up the kinetic energy in said mechanism for subsequent application in overcoming the static inertia of said other part when said driven member is released by said rotation checking means.

3. In a cinematograph, a film-shutter-and-transport drive shaft, means movable into and out of position for checking the rotation of said shaft, a gear train connecting said shaft with a motor, said gear train including a pair of cylindrical parts, a coiled spring connecting said parts in driving relation, said spring having characteristics of resilience adapting it to stop the motor when rotation of said drive shaft is checked, to permit one of said parts to overrun the other part when the rotation of said drive shaft is checked, and to maintain said parts at equal speeds during periods of rotation of said shaft, other means adapted to hold said one part in its overrun position thereby storing up the kinetic energy in said gear train for subsequent application in overcoming the static inertia of said drive shaft when said drive shaft is released by said rotation checking means.

4. In a cinematograph including a rotatable drive shaft, driving mechanism for the shaft comprising a motor and gearing, and a device movable into and out of position for checking rotation of the shaft; means interposed between the shaft and driving mechanism comprising driving and driven rotatable parts connected respectively with the gear train and with the shaft, and a spring connecting said parts in driving and driven relation, said spring having characteristics of resilience adapting it to stop the motor upon checking of the shaft rotation, to permit overrun of the driving part to a degree limited substantially to store the kinetic energy in the operating driving mechanism when such stopping occurs for subsequent release quickly to bring said shaft to operating speed upon release of the shaft, and to maintain said driving and driven parts at equal speeds following such release of stored energy.
